Primary Examiner — John Windmuller(74) *Attorney, Agent, or Firm* — Tarolli, Sundheim, Covell & Tummillo LLP(57) **CLAIM**

The ornamental design for an antenna, as shown and described.

DESCRIPTION

FIG. 1 is a perspective top view of an antenna;
FIG. 2 is a perspective bottom view of the antenna;
FIG. 3 is a first side elevation view of the antenna;
FIG. 4 is a second side elevation view of the antenna;
FIG. 5 is a third side elevation view of the antenna;
FIG. 6 is a fourth side elevation view of the antenna;
FIG. 7 is a top plan view of the antenna; and,
FIG. 8 is a bottom plan view of the antenna.
The broken and dashed lines shown are for environmental purposes only and form no part of the claimed design.
